SHAMPOO TANK FOR A FLOOR CLEANING MACHINE OR THE LIKE

Charles V. Durkee, Indianapolis, Ind., assignor to Earl Grissmer Company, Inc., Indianapolis, Ind.

Filed Apr. 10, 1974, Ser. No. 459,596

Term of patent 14 years

Int. Cl. D7—05

U.S. Cl. D7—170

T1 Q.3.

T1 Q.4.

T1 Q.2.

T1 Q.1.

FIG. 6.

FIG. 1 is a front elevational view of a shampoo tank for a floor cleaning machine or the like showing my new design;

FIG. 2 is a side elevational view thereof;

FIG. 3 is a rear elevational view thereof;

FIG. 4 is a top plan view thereof;

FIG. 5 is a side elevational view thereof shown mounted on a floor cleaning machine which is shown in broken lines for illustrative purposes only and forms no part of the claimed design; and

FIG. 6 is a plan view thereof.

I claim:

The ornamental design for a shampoo tank for a floor cleaning machine or the like, as shown and described.
